UNITED STATES PATENT OFFICE.

MORRIS G. ROSENTHAL, OF MENTOR, OHIO.

KNITTING-MACHINE.

1,082,239.

Specification of Letters Patent. Patented Dec. 23, 1913.

Application filed February 12, 1913. Serial No. 747,960.

To all whom it may concern:

Be it known that I, MORRIS G. ROSENTHAL, citizen of the United States, residing at Mentor, in the county of Lake and State of 5 Ohio, have invented certain new and useful Improvements in Knitting-Machines, of which the following is a specification.

This invention relates to knitting machines of the cylinder and dial type, in 10 which two sets of needles are employed for the production of a ribbed fabric, especially a double faced fabric having the back and front of different materials. In knitting fabric of this kind on coarse gages it is not 15 necessary to have any special construction at the drawing or casting off points of the dial or cylinder needles, and an ordinary rib knitting machine may be used for the purpose. But in fine gages it is impossible to 20 use the ordinary construction for drawing in the full amount of loop used by the dial needles, which loops are drawn through the loops of the cylinder needles, for the reason that several needles would be drawing loops 25 at the same time, and the increased or excess tension tears the yarn. I remedy this defect by using the needles as jacks or blades to supply the amount of yarn needed by each 30 needle, and I do this by holding the latches of the needles closed by means of a guard, so that they draw the loops to the extent necessary to produce the fabric, before the 35 loops are interknit and cast off.

The invention is illustrated in the accompanying drawings in which—

Figure 1 is a development of a portion of the cylinder and its needles. Fig. 2 is a development of a portion of the dial and its needles. Fig. 3 is a perspective view of a 40 part of the machine. Fig. 4 is a vertical section on the line 4—4 of Fig. 3. Fig. 5 is a detail in perspective of the latch closer.

The yarns or threads are indicated *a* and *b* and will be supplied to the machine by 45 any suitable means. The former is laid along the cylinder needles and the latter upon the dial needles, the cylinder needles being indicated at 22 and the dial needles at 21, carried in grooves to reciprocate in the 50 usual manner.

Referring first to the action of the cylinder needles, the yarn *a* is taken in at the eye 8 of the yarn guide and laid across the raised ends of the needles and is taken in by the

hocks thereof as in any ordinary machine. 55 The cams are mounted on the cam cylinder 40, and the needles are first drawn down by the cam 1, drawing the thread or yarn down over the dial needles, which are then advanced, at a point 10 (Fig. 2) back of the 60 open latches of said dial needles, to the low point indicated at 4 (Fig. 1) just below the upper edge of the cylinder 41. At this point the old loops or partly complete stitches are cast off of the cylinder needles, and new 65 loops are formed by said needles with the new yarn so taken in. The cylinder needles are then forced up by the cam 3 to a point above the edge of the cylinder as indicated at 5. As the needles draw down at the point 70 4 the latches thereof are closed and held closed by a latch holder 20, to be hereinafter referred to, so that said needles act as blades or jacks for forming loops or "sinking", to a certain extent, the yarn of the dial needles. 75 After the dial loops are formed (while the cylinder needles are at point 5) the cylinder needles are drawn down by the cam 2 (Fig. 1) and the loops taken in at the point 4 are formed into complete stitches at the point 80 indicated at 6 in Fig. 1. The loops cast off at point 4 cannot be formed into complete stitches until free from the dial needles, that is, until the remainder of the loops (formed at point 4) are cast off by the dial needles at 85 the point 6, the dial needles being advanced between the cylinder needles between points 4 and 6. It will be seen that the cam 3 in connection with the latch holder 20 holds the cylinder needles up to form blades or 90 jacks while the dial loops are being made.

Referring now to the action of the dial needles 21, the yarn *b* is laid thereon by the separate yarn guide having an eye 17 for the 95 yarn. The needles are then drawing in from the point 14 (Fig. 2) to the point 11, by action of the cam 15, and the needles start to draw back at said point 14 after the yarn of the cylinder needles has been looped (by action of the cam 1) over the dial needles at 100 points in back of the latches of the dial needles, which are open at this point, and when the dial needles draw back of the feed point 17 the latches thereof are closed by means of the latch closer and holder 7 which, 105 as shown in Fig. 3, rests with spring pressure on the needles at the point indicated at 18 in Fig. 2, and as the needles draw in at

this point the latches are closed over the yarn taken in at the eye 17. The latch closer 7 relieves the strain on the yarn by closing the latch, instead of using the yarn to close the latches as in ordinary machines, and holds the latches closed until the needles are retracted beyond the same. At the point 11, Fig. 2, the yarn of the dial needles is drawn around the closed latches of the cylinder needles, then at the point 5 on Fig. 1, and those needles act as jacks for the purpose of drawing the necessary amount of yarn to form the loops of the dial needles, and by means of the cam 16 the series of loops are held at the point 12 and finally drawn into stitches at the point 13 opposite the drawing in point 6 of the cylinder needles; after which both sets of needles are advanced for the next operation in the usual manner. It will be seen that in consequence of this operation the cylinder needles, when advanced to the point 5, act as blades or sinkers for the yarn loops of the dial needles, and said dial needles, when advanced to the point 12, act as blades or sinkers for the yarn loops of the cylinder needles; therefore each set of needles is advanced to serve as sinkers for the yarn loops of the other set.

Fig. 4 shows a sectional view of the cylinder and dial with the needles in position at the highest point of cam 3, Fig. 1, said needles being indicated at the point indicated at 5, and 20 is a needle latch guard supported on the cam cylinder for holding the latches of the cylinder needles closed while said needles are acting as blades for the dial loops. The dial needle 21 is shown with a loop partly formed around the cylinder needle.

As indicated in Fig. 1, the cams 1 and 3 are preferably fastened to adjustable supports 9 resting on springs 18 and held by means of set screws in the cam cylinder.

In Fig. 3 the latch closer is shown in position. It comprises a lever or arm 27 to which is fastened, by set screw 29, a small blade or knife edged piece 7 which rests on the dial needles back of the latches thereof, which are then open, and as the needles draw in the latches are swung over and closed. The arm 27 is pivoted at 28 and has connected thereto a spring 26 which presses the blade 7 down upon the needles. The spring 26 is connected to an adjustable arm 24 having a slot with a screw 25 attaching the same to the bracket 23, and permitting the tension of the spring to be varied to get more or less pressure on the needles. The bracket 23 is fastened to the cam cylinder 60 and is slotted for adjustment to set the latch closer in proper position.

By the means described, fine gage double faced fabric may be formed of different materials and the amount of material required by the dial needles is assured by using the

cylinder needles as blades to provide sufficient slack and avoid breaking the yarn knitted by the dial needles.

What I claim as new is:

1. A knitting machine having, in combination, two sets of latch needles, operating devices for advancing and retracting said needles, including means for advancing needles of one set at a point between the drawing and complete stitch forming positions, and means for holding the latches of said advanced needles closed at said point, whereby said needles act as blades or jacks for looping the yarn drawn by the other set of needles. 70 75

2. A knitting machine having, in combination, two sets of needles, a yarn feed for each set, knitting cams for operating said needles, a cam acting to advance the needles of one set, between the drawing and complete stitch forming positions, to a position where they will act as blades for looping the yarn drawn by the other set of needles, and means for holding the latches of said advanced needles closed while they are so acting. 80 85

3. A knitting machine having, in combination, two sets of latch needles, operating devices for said needles, a latch holder, located between the feeding and complete stitch forming points of one set of needles, for holding closed the latches of said set of needles, after they take the yarn, means for advancing said set of needles, while closed, to form sinking blades, and means for looping the yarn of the other set of needles around said closed needles. 90 95

4. A knitting machine having, in combination, two sets of latch needles, operating devices for said needles, and a latch holder located between the feeding and complete stitch forming points of one set of needles, for holding closed the latches of said set of needles, after they take the yarn, said latch holder comprising a spring pressed blade 110 bearing on the needles behind the latches when the needles are advanced to feeding position. 105

5. A knitting machine having, in combination, two sets of latch needles, operating devices for said needles, means operating on the needles of each set between the feeding and complete stitch forming positions for holding closed the latches of said needles after they take the yarn, means for advancing the needles of each set, while so closed, to form blades for the other set, and means for thereafter retracting the needles, to complete the stitches. 115 120

6. A knitting machine having, in combination, two sets of latch needles, operating devices for said needles, and a latch holder operating on the needles of each set between the feeding and complete stitch forming positions, for closing the latches of said 125 130

needles after they take the yarn, and cams acting on the needles of each set to advance the same while the latches thereof are so closed, whereby the needles of each set will 5 act as blades for drawing the yarn of the other set of needles.

7. A knitting machine having, in combination, sets of cylinder and dial latch needles, knitting cams for advancing and 10 retracting said needles, a cam acting on the cylinder needles between the feeding and complete stitch forming positions to advance the same between the dial needles as the latter are retracting, and a latch 15 holder 20 for holding the latches of the cylinder needles closed when they are so advanced.

8. A knitting machine having, in combination, sets of cylinder and dial latch needles, knitting cams for advancing and 20 retracting said needles, and a latch closer and holder for the dial needles comprising a blade pressing on the same beyond the point at which said needles form loops, a pivoted arm to which the blade is attached, 25 and a spring connected to the arm, to press the blade against the needles.

In testimony whereof, I do affix my signature in presence of two witnesses.

MORRIS G. ROSENTHAL.
